UNITED STATES PATENT OFFICE

119,073

DESIGN FOR SUNGLASSES

Marcel Rochas, Paris, France

Application June 21, 1939, Serial No. 85,608
In France April 24, 1939

Term of patent 7 years

To all whom it may concern:

Be it known that I, Marcel Rochas, a citizen of the Republic of France, residing at Paris, France, have invented a new, original, and ornamental Design for Sunglasses, of which the following is a specification, reference being made to the accompanying drawing, forming a part thereof.

The figure is a front perspective view of sunglasses showing my new design.

I claim:

The ornamental design for sunglasses, substantially as shown.

MARCEL ROCHAS.
